METHOD OF PROVIDING A NEW PRODUCT

Jacquelin E. Harvey, Jr., Washington, D. C., and Robert H. White, Jr., and Joseph A. Vaughan, Atlanta, Ga., assignors of one-half to said Harvey, Jr., and one-half to Southern Wood Preserving Company, East Point, Ga., a corporation of Georgia

No Drawing. Application December 21, 1942,
Serial No. 469,723

8 Claims. (Cl. 196—50)

The instant invention relates to the production of toxic oils employable as fungicides, insecticides, and for any other service to which toxic oils may be put.

More especially the instant invention relates to the production of toxic oils from mixtures of petroleum fractions characterized by ring structure content. Among such starting materials may be mentioned mixtures of petroleum fractions characterized by ring structure content recovered from petroleum fractions by well known extraction methods including extractive distillation and azeotropic distillation. Also may be mentioned mixtures of petroleum fractions characterized by ring structure content as flowing from thermal and/or catalytic treatment of certain petroleum fractions which includes petroleum fractions having ring structures induced in the course of thermal and/or catalytic treatment, as for example having ring structures induced in the course of one or more thermal and/or catalytic treatments of unusual length, as for example, for periods of from 1-10 hours or more.

An object of the instant invention is the production of toxic oils from the aforesaid petroleum fractions or others whereby to provide oils of the preservative type, as for example preservative wood impregnants conforming to specifications extant or acceptable to the trade consuming such oil materials.

Another object of the instant invention is the provision of preservative wood impregnants having boiling ranges and residues in accordance with published specifications and/or in accordance with consumer preference.

Another object of the instant invention is the reforming, modifying, converting and/or transforming of the mixtures of hydrocarbons whereby to induce toxicity.

Another object of the instant invention is the unveiling of latent toxicity in mixtures of petroleum fractions having inherent but inhibited toxicity.

Another object of the instant invention is the coordination of process variables so as to provide specific gravities within definite limits in various fractions of the beneficiated material.

Another object of the instant invention is a coordination of process variables which will provide in various fractional parts of the beneficiated material cyclic structures with specific

gravities falling within the limits hereinafter stated.

Another object of the instant invention is the induction of toxicity in the presence of a reforming catalyst adapted to favorably influence the induction of toxicity. By the expression "a reforming catalyst" is meant a catalytic material adapted to favorably exert catalytic influence whilst the starting material is being reformed, transformed, modified and/or converted in accordance with the instant process whereby to induce toxicity. In the specification and in the annexed claims, reformation, transformation, conversion and/or modification of the starting material whereby to induce toxicity are specifically meant to include cracking, addition, substitution and/or subtraction reactions that are possible within the limits of the process variables disclosed elsewhere herein.

20 In the past wood preservative oils of the high temperature coal tar derived type have been employed in quantities greatly exceeding the total of all other wood preservative oils. From the standpoint of availability of said coal tar as the parent product of wood preservative oils, it is annually produced in this country under normal conditions to the extent of five hundred million to six hundred million gallons. This quantity of coal tar is capable of yielding an amount of highly effective wood preservative oils which would make this country self sufficient in its wood preservative requirements. However, due to the fact that when a wood preservative distillate (creosote) is recovered from coal tar there remains in the still a residue (pitch) which, at best, is a low priced product and which, at worst, is a seriously distress product to the end that at times it is placed in inventory rather than sold, the current method of processing coal tar leaves much to be desired. The net result of this situation obtaining is that the coal tar distiller usually confines himself to that distillation recovery of creosote which would correspond to the attending amount of pitch that he can market at a profit. Accordingly, over a period of years several hundred million gallons of creosote oil have been imported into this country. That such a situation should obtain is apparently a paradox in that we annually produce a quantity of high temperature coal tar which if processed to yield creosote would make us self-sufficient in that requirement. A survey of this paradox is fully outlined in an address

given by no less an authority than S. P. Miller, technical director, The Barrett Company, 40 Rector Street, New York city, before the Franklin Institute, Philadelphia, Pennsylvania, in December, 1932. The economics of coal tar have not materially changed since that date.

In view of the apparent inability of the coal tar industry to provide national needs of wood preservative oils, a strong incentive is given to groups processing other types of oil to invade the lucrative wood preservative market. At the present time many types of aromatic oils are produced by the petroleum industry, and the high boiling oils of aromatic content produced by this industry have for several years been tested for their wood preservative efficiency.

By the term "petroleum aromatic" as used herein and in the appended claims is meant to include mixtures of petroleum fractions characterized by cyclic content and include specifically various forms and types of naphthalenes found in various mixtures of petroleum fractions, as for example monocyclic and polycyclic naphthalenes.

The so-called petroleum aromatics which include the monocyclic and polycyclic naphthalenes and unsaturated hydrocarbon fractions have in the past been produced in very large quantities. However, very little work has been done on these materials. Such a fact is borne out on page 667, "Reactions of pure hydrocarbons" Gustav Egloff, Reinhold Publishing Corporation, 330 West 42nd Street, New York city, which states:

"Despite the fact that naphthalenes or cyclo-paraffines are available in enormous quantities, as shown by an estimate of 100,000,000 barrels present in the 1,498,000,000 barrels of crude oil which was the world's production in 1934, comparatively little work of a pyrolytic nature has been performed on individual naphthalene hydrocarbons or the cycloolefins."

Several oils of cyclic content produced by the petroleum industry have been inspected for their toxicity to wood destroying fungi, among which may be mentioned a high boiling oil of cyclic content produced (1940) at the Wood River Refinery of the Shell Oil Company and which has the following inspection:

* Maximum.

In the foregoing tabular data P. M. C. C. means Pensky Martin Closed Cup; C. O. C. means Cleveland Open Cup.

Upon evaluating the foregoing oil for its toxicity to wood destroying fungi (Madison 517), it

was found that this oil did not inhibit the growth of the fungi named at a concentration of up to and including 10%.

It is now discovered that the oil above named or other oils of cyclic content produced by the petroleum industry can be increased in toxicity in accordance with the process of the instant invention.

According to the instant invention oils of cyclic content produced by the petroleum industry are reformed, transformed, modified and/or converted to oils of a more toxic nature having characteristics acceptable to consumers of wood preservative impregnant and/or conforming to wood preservative specifications extant.

We have discovered that the relatively non-toxic petroleum oils of cyclic content mentioned in the foregoing, or others, contain toxicity diluents which inhibit an inherently toxic molecular structure.

We have further discovered that by thermally and/or catalytically treating these said petroleum oils of inhibited toxicity in the presence of certain substances, as for example certain oils and/or gas or gases, we are able to transfer the toxicity diluents from the former to the latter, and thus unveil the latent toxicity in the former.

The following examples will serve to illustrate several modes of practicing the present invention.

- Example 1.—A liquid sulfur dioxide extract of a mixture of petroleum fractions, said extract having an initial boiling point of about 250° C., substantial residual matter above 355° C. and characterized by inherent but inhibited toxicity due to the presence of toxicity diluents, is commingled with benzene, with or without heating as necessity may dictate in order to form a relatively smooth comminglement. Precipitated sludge, if any, may be discarded if desired. The comminglement represents one part of the aromatic extract and two parts of benzene.

The comminglement is heated in the presence of an activated clay catalyst at a temperature of 460° C. whilst under a pressure of 1,000 pounds for such a length of time as to jointly provide (1) transference of toxicity diluents from the molecular structure of the aromatic extract to the benzene, (2) newly formed low boiling materials due to the cracking of the extract, as for example newly formed materials boiling at or below 235° C., and (3) an overall specific gravity in fractional parts of the beneficiated oil extract falling between the limits noted in the following tabular data:

	Fractions	Low limit	High limit
235-270° C		0.850	1.0315
270-315° C		0.914	1.0691
315-355° C		0.973	1.1175

and preferably between the limits noted below:

	Fractions	Low limit	High limit
235-270° C		0.878	1.0165
270-315° C		0.942	1.0541
315-355° C		1.001	1.1025

70 When processing the aromatic extract in accordance with the foregoing disclosure, a period of one hour will illustratively serve to provide (1) transference of toxicity diluents from the molecular structure of the aromatic extract to the benzene, (2) newly formed low boiling frac-

tions boiling at least as low as about 235° C. due to the cracking of the extract and (3) a specific gravity in fractional parts of the beneficiation falling between the preferred stated limits.

At the end of the stated period of processing the oil is withdrawn from its treating enclosure, cooled and inspected. The unreacted benzene, if any, and the benzene containing at least a portion of the former toxicity diluents of the aromatic extract are removed, partially or substantially totally from the overall beneficiation in any suitable manner, as for example by distillation or the like.

After the total or partial removal of said benzenes, the beneficiated aromatic extract is found to have enhanced toxic properties as jointly flowing from, among other things, the formation of newly created low boiling materials boiling at or below 235° C. and the transference of the toxicity diluents to the benzene.

After the partial or total removal of said benzenes from the beneficiated extract which has substantial residual matter above 355° C., the beneficiated extract may be used in entirety as a preservative wood impregnant having commercial toxicity, or a preservative wood impregnant may be segregated therefrom in any well known manner complying with specifications extant and/or consumer preference.

As examples of wood preservative impregnants of the oil derived type that are meeting with consumer preference and which may be produced or paralleled by the process of the present invention, the following tabular data show several published specifications:

WOOD PRESERVATIVE IMPREGNANTS:
Specifications

1. American Wood Preservers' Association
  - a. Up to 210° C., not more than 5%.
  - b. Up to 235° C., not more than 25%.
2. American Wood Preservers' Association
  - a. Up to 210° C., not more than 1%.
  - b. Up to 235° C., not more than 10%.
  - c. Up to 355° C., not less than 65%.
3. American Wood Preservers' Association
  - a. Up to 235° C., not more than 1½%.
  - b. Up to 300° C., not more than 16½%.
  - c. Up to 355° C., not less than 45%.
4. American Wood Preservers' Association
  - a. Up to 210° C., not more than 8%.
  - b. Up to 235° C., not more than 35%.
5. American Wood Preservers' Association
  - a. Up to 210° C., not more than 10%.
  - b. Up to 235° C., not more than 40%.
6. American Wood Preservers' Association
  - a. Up to 210° C., not more than 5%.
  - b. Up to 235° C., not more than 15%.
7. Prussian Ry.
  - a. Up to 150° C., not more than 3%.
  - b. Up to 200° C., not more than 10%.
  - c. Up to 235° C., not more than 25%.
8. National Paint Varnish & Lacquer Association #220.
  - a. 5% at 162° C.
  - b. 97% at 270° C.
9. Southern pine shingle stain oil
  - a. 5% at 137° C.
  - b. 95% at 257° C.
10. Neville shingle stain oil
  - a. I. B. P., 150° C.
  - b. 5% at 205° C.
  - c. 95% at 292° C.
11. Carbolineum 270° C., I. B. P. 75

By the nature of the process it is obvious that modifications of existing specifications, or other and more exacting specifications may be met.

The specific gravities of the fractional parts of the beneficiated extract noted in the foregoing are critical within limits. Unless the lower limit is approximated toxicity unveiling will be sacrificed. If an attempt is made to exceed the upper limit, as for example the preferred upper limit, unwanted reactions occur. The induction and/or provision of the noted specific gravities in fractional parts of the beneficiated extract, and more especially the preferred specific gravities, is a valid test for the induction of toxicity in the fractions referred to, and further is an indication that toxicity has been induced in other fractions of the material under treatment.

Instead of employing benzene, the destructive reforming of the petroleum aromatic may be carried on in the presence of any material of ring structure content possible of receiving into its molecular structure the cleavage toxicity diluents from the starting material. Among these materials may be mentioned various naphthenes and aromatics, as for example, but not as a restriction, toluol, xylol, trimethylbenzene, naphthalene or the like, and specifically the various naphthenes capable of receiving into their molecular structure said cleavage diluents.

Example 2.—Practice the process of Example 1 with pelleted Bentonite clay as catalytic material.

Example 3.—Practice the process of Example 1 with activated attapulgus clay as catalytic material.

Example 4.—Practice the process of Example 1 with a silica hydrogel as catalytic material.

Example 5.—Practice the process of Example 1 with a silica hydrogel impregnated with an aluminum salt as catalytic material.

Example 6.—Practice the process of Example 1 with bentonite and an adsorptive clay as catalytic materials.

Example 7.—Practice the process of Example 1 with a silicious material impregnated with a metallic oxide as catalytic material.

Example 8.—Practice the process of Example 1 with a silicious material impregnated with a metallic sulfide as catalytic material.

Example 9.—Practice the process of Example 1 with coprecipitated alumina and chromia hydrogels as catalytic materials.

Example 10.—A furfural extract of a mixture of petroleum fractions, said extract boiling entirely between 240-380° C., and characterized by toxicity diluents comprising integral parts of materials of cyclic structure content, said cyclic structures having inherent but inhibited toxicity as stemming from the presence of said diluents, is commingled with toluol whilst in a heated condition sufficient to provide a smooth blend. Residual sludge, if any, incidental to the blending operation may be discarded if desired. The toluol 65 represents 60% of the blend.

The mixture of materials is subjected to a temperature of 470° C. whilst under a pressure of 2,000 pounds for such a period of time as to jointly provide (1) newly formed low boiling materials boiling below 235° C. due to the cracking of the extract, (2) transference of at least a portion of the toxicity diluents from the molecular structure of the aromatic extract to the toluol and (3) an overall specific gravity in fractional

parts of the beneficiated extract falling between the limits noted in the following tabular data:

Fractions	Low limit	High limit
270-315° C.	0.914	1.0691
315-355° C.	0.973	1.1175

and preferably between the limits noted below:

Fractions	Low limit	High limit
270-315° C.	0.942	1.0541
315-355° C.	1.001	1.1025

When processing the furfural extract under the conditions above named, a period of one hour and 15 minutes will illustratively serve to jointly provide (1) the stated newly formed low boiling materials, (2) transference of toxicity diluents as noted and (3) a specific gravity in fractional parts of the beneficiation falling between the preferred stated limits.

When the stated period of processing has been completed, the oil is withdrawn from its treating enclosure, cooled and inspected. The unreacted toluol, if any, and the toluol containing at least a portion of the former toxicity diluents of the aromatic extract are totally or partially removed from the overall beneficiation in any suitable manner, as for example by distillation or the like.

After the total or partial removal of the toluols, the beneficiated furfural extract is found to have enhanced toxic properties as jointly stemming from, among other things, the formation of the newly created low boiling materials and the transference of toxicity diluents to the toluol.

The beneficiated extract of induced toxic properties which has substantial residual matter above 355° C. may be used in toto as a wood preservative or if desired a wood preservative having specification boiling characteristics may be segregated therefrom.

The specific gravities of the materials of cyclic structure content in fractional parts of the beneficiated extract noted in the foregoing are critical within limits. Unless the lower limit is approximated toxicity unveiling will be sacrificed. If an attempt is made to exceed the upper limit, as for example the preferred upper limit, polymerization and/or inordinate gasification will occur.

The induction and/or provision of the stated specific gravities in fractional parts of the beneficiated extract is a valid test for the induction of toxicity in the fractions referred to, and further is an indication that toxicity has been induced in other fractions of the material under treatment.

Example 11.—Practice the process of Example 10 in the presence of a molybdenum oxide catalyst.

Example 12.—Practice the process of Example 10 with molybdenum and tin oxides as catalytic materials.

Example 13.—Practice the process of Example 10 with chromium oxide as catalytic material.

Example 14.—Practice the process of Example 10 with vanadium oxide as catalytic material.

Example 15.—Practice the process of Example 10 with tin oxide as catalytic material.

Example 16.—Practice the process of Example 10 with molybdenum sulfide as catalytic material.

Example 17.—Practice the process of Example 10 with cromium sulfide as catalytic material.

Example 18.—Practice the process of Example 10 with vanadium sulfide as catalytic material.

Example 19.—Practice the process of Example 10 with tin sulfide as catalytic material.

Example 20.—Practice the process of Example 10 with coprecipitated oxides of copper and chromium as catalytic materials.

Example 21.—One part of a petroleum oil characterized by induced cyclic structures having toxicity diluents, said oil having an initial boiling point of about 200° C. and about 90% over at 400° C. is commingled with two parts of benzene. Seven percent of zinc chloride is employed as the catalyst. The mixture and catalyst are charged to a rocking autoclave and heated to a temperature of 210° C. whilst under autogenous pressure for such a length of time as to jointly provide (1) newly formed lower boiling fractions of the petroleum above mentioned, (2) transference of toxicity diluents from the molecular structure of the charging stock to the benzene and (3) an overall specific gravity in the materials boiling between 315-355° C. of the beneficiation falling between 0.973-1.1175, and preferably between 1.001-1.1025.

When processing the starting material in accordance with the foregoing disclosure, a period selected between the limits of one and two hours, as for example one and one-half hours, will serve illustratively to jointly provide (1) the stated newly formed low boiling fractions, (2) transference of the toxicity diluents from the starting material to the benzene and (3) a specific gravity in the 315-355° C. fraction of the beneficiation falling between the preferred stated limits.

At the end of the processing period, the agitation of the bomb is stopped and the catalyst mass is allowed to settle to the bottom. After the catalyst mass has settled, the overlying layer of oil, without catalyst, is withdrawn and cooled. The unreacted benzene and the reacted benzene which contain as an integral part at least a portion of the toxicity diluents previously comprising an integral part of the starting material, are partially or totally removed from the beneficiated feed stock in any suitable manner, as for example by distillation. After removal of the said benzene, the beneficiated material may be used in toto as a wood preservative, or a wood preservative of desired boiling range may be segregated therefrom.

The induction and/or provision of the noted specific gravity, and preferably the preferred specific gravity in the materials boiling between 315° C. and 355° C. of the beneficiation is a valid test for the induction of toxicity in the fraction referred to, and further is an indication that toxicity has been induced in other fractions of the material under treatment.

Example 22.—Practice the process of Example 21 with aluminum chloride as catalytic material.

Example 23.—Practice the process of Example 21 with potassium chloride as catalytic material.

Example 24.—Practice the process of Example 21 with ammonium chloride as catalytic material.

Example 25.—Practice the process of Example 21 with zirconium chloride as catalytic material.

Example 26.—Practice the process of Example 21 with iron chloride as catalytic material.

Example 27.—Practice the process of Example 21 with manganese chloride as catalytic material.

Example 28.—Practice the process of Example 21 with tin chloride as catalytic material.

Example 29.—Practice the process of Example 21 with iodine as catalytic material.

Example 30.—Practice the process of Example 21 with iodofrom as catalytic material.

Example 31.—Practice the process of Example 21 with hydriodic acid as catalytic material.

Example 32.—Practice the process of Example 21 with bromine as catalytic material.

Example 33.—Practice the process of Example 21 with a hydrogen halide as catalytic material.

Example 34.—A liquid sulfur dioxide extract of a mixture of high boiling petroleum fractions, said extract having an initial boiling point of about 260° C., substantial residual matter above 355° C. and characterized by inherent but inhibited toxicity due to the presence of toxicity diluents is commingled with benzene, with or without additional heating as necessity may dictate in order to provide a relatively smooth comminglement. In the event sludge is precipitated, it may be discarded if desired. The comminglement comprises one part of aromatic extract and two parts of benzene.

The blended materials are heated in the presence of an activated clay catalyst at a temperature of 440° C. whilst under a pressure of 1200 pounds for such a length of time as to jointly provide (1) transference of toxicity diluents from the molecular structure of the aromatic extract to the benzene, (2) newly formed materials boiling below 235° C. due to the cracking of the extract and (3) a specific gravity of materials of cyclic structure content in fractional parts of the beneficiated material falling between the limits noted in the following tabular data:

Fractions	Low limit	High limit
235-270° C.	0.935	1.0756
270-315° C.	0.973	1.0933
315-355° C.	1.027	1.1285

and preferably between the limits noted below:

Fractions	Low limit	High limit
235-270° C.	0.963	1.0606
270-315° C.	1.001	1.0783
315-355° C.	1.055	1.1135

When processing the aromatic extract according to the instant example, a period of one hour and 15 minutes will illustratively serve to provide (1) transference of toxicity diluents from the molecular structure of the aromatic extract to the benzene, (2) newly formed low boiling materials as stated and (3) a specific gravity of materials of cyclic structure content in fractional parts of the beneficiation falling between the preferred stated limits.

When the processing period has been completed, the oil is withdrawn from its treating enclosure and cooled. After removal, at least in part, of the unreacted benzene and the benzene containing at least a portion of the former toxicity diluents of the aromatic extract, as for example by distillation, the beneficiated extract is found to have enhanced toxic properties as jointly flowing from, among other things, the formation of newly created low boiling materials and the transference of toxicity diluents to the benzene.

After the partial or total removal of said benzenes from the beneficiated extract which has substantial residual matter above 355° C., the beneficiated extract may be used *in toto* as a

preservative wood impregnant having commercial toxicity, or a preservative wood impregnant may be segregated therefrom complying with boiling range specifications extant and/or consumer preference.

The induction and/or provision of the specific gravities of materials of cyclic structure content in fractional parts of the beneficiation noted in the foregoing is a valid test for the induction of toxicity in the fractions referred to, and further is an indication that toxicity has been induced in other fractions of the material under treatment.

Example 35.—A furfural extract of a mixture of petroleum lubricating fractions, said extract characterized by toxicity diluents comprising integral parts of the materials of cyclic structure content having inherent but inhibited toxicity because of the presence of said diluents, is commingled with toluol whilst in a heated condition sufficient to provide a smooth blend. Residual sludge, if any, incidental to the blending operation may be discarded if desired. The toluol represents 50% of the blend.

The mixture of materials is subjected to a temperature of 460° C. whilst under a pressure of 800 pounds for such a period of time as to jointly provide (1) newly formed materials boiling below 235° C. due to the cracking of the extract, (2) transference of at least a portion of toxicity diluents from the molecular structure of the aromatic extract to the toluol and (3) a specific gravity of materials of cyclic structure content in fractional parts of the beneficiation falling between the limits noted in the following tabular data:

Fractions	Low limit	High limit
270-315° C.	0.973	1.0933
315-355° C.	1.027	1.1285

and preferably between the limits noted below:

Fractions	Low limit	High limit
270-315° C.	1.001	1.0783
315-355° C.	1.055	1.1135

When processing the furfural extract in accordance with the instant example, a period of about one hour will illustratively serve to jointly provide (1) the stated low boiling materials, (2) transference of toxicity diluents as noted and (3) a specific gravity of materials of cyclic structure content in fractional parts of the beneficiation falling between the preferred stated limits.

When the stated period of processing has been completed, the oil is withdrawn from its treating enclosure, cooled and inspected. The unreacted toluol, if any, and the toluol containing at least a portion of the former toxicity diluents of the aromatic extract are totally or partially removed from the overall beneficiation in any suitable manner, as for example distillation or the like.

After the partial or total removal of the toluols, the beneficiated furfural extract is found to have enhanced toxic properties as jointly stemming from, among other things, the formation of the newly created low boiling materials and the transference of toxicity diluents to the toluol.

The beneficiated extract may be handled in

accordance with the disclosures made in the foregoing.

The induction and/or provision of the specific gravities of materials of cyclic structure content in fractional parts of the beneficiated material falling between the limits noted in the foregoing is a valid test for the induction of toxicity in the fractions referred to, and further is an indication that toxicity has been induced in other fractions of the material under treatment.

Example 36.—One part of a flashed petroleum residuum having an initial boiling point of about 300° C. and an end point of about 425° C., characterized by induced cyclic structures having toxicity diluents as integral parts of said cyclic structures is commingled with two parts of benzene. Eight percent of aluminum chloride is employed as catalytic material. The mixture and catalyst are charged to a rocking autoclave and heated to a temperature of 175° C. whilst under autogenous pressure for such a length of time as to jointly provide (1) newly formed materials boiling below 200° C., (2) transference of toxicity diluents from the molecular structure of the charging stock to the benzene and (3) a specific gravity of materials of cyclic structure content in the materials boiling between 315-355° C. of the beneficiated material falling between the limits of 1.027-1.1285, and preferably between the limits of 1.055-1.1135.

When employing the process variables disclosed in the instant example, a period of one hour will illustratively serve to jointly provide (1) the stated newly formed low boiling fractions, (2) transference of toxicity diluents from the starting material under treatment to the benzene and (3) a specific gravity of materials of cyclic structure content in the fraction 315-355° C. of the beneficiation falling between the preferred stated limits.

When the processing period has been completed, the agitation of the bomb is stopped and the catalyst mass is allowed to settle to the bottom. After the catalyst mass has settled, the overlying layer of oil is withdrawn and cooled. The unreacted benzene, if any, and the reacted benzene which contains as an integral part at least a portion of the toxicity diluents previously comprising an integral part of the flashed residuum, are partially or totally removed from the beneficiated feed stock in any suitable manner, as for example by distillation. After removal of said benzenes, the beneficiated feed stock may be used in its overall entirety as a preservative wood impregnant, or a wood preservative impregnant of desired boiling range may be segregated therefrom in any well known manner, as for example by providing a stabilized residual, a distillate or an extract.

The induction and/or provision of the noted specific gravity of materials of cyclic structure content in the fraction 315-355° C. of the beneficiation is a valid test for the induction of toxicity in the fraction referred to, and further is an indication that toxicity has been induced in other fractions of the material under treatment.

In the instant process various pressures are employable. As for example, but not as a restriction, pressures ranging from a few hundred pounds and upward, and pressures as high as practicable may be employed.

The temperatures of the instant process when carrying on the operation without a catalyst, or with a catalyst of the silicious type, metallic oxides or sulfides and halogens, halids and derivatives thereof, excluding the chlorides, are selected between the limits of about 350-600° C., and preferably between 400-500° C. When employing a metallic chloride or the like the temperatures are selected between 70-225° C., and preferably between 150-200° C. Under certain circumstances, various halogens, halids and derivatives thereof, including specifically substitution and addition products thereof, as for example and specifically substitution and addition products of said derivatives may be employed at a temperature selected between the limits of 70-225° C.

The time of treatment will vary according to the raw material being processed and the material which is selected to act as the toxicity diluent recipient. A few trials with any given starting material will enable those skilled in the art to equal or approximate the objectives set forth in the foregoing examples.

20 The volume of the liquid material which acts as the recipient of the toxicity diluents of the starting material may vary over relatively wide limits, as for example it may represent as little as 25% of the mixture, and may go as high as 25 two or three times the volume of the starting feed stock. Preferably the volume of this liquid is equal to not less than that of the feed stock, nor more than twice the volume of the feed.

25 The process of the instant invention may be practiced in an intermittent processing vessel or in a continuous manner as will become apparent to those skilled in the art after having read the foregoing disclosures.

30 In the examples shown in the foregoing, one or 35 more phases, etc. of one example may be added to or substituted for other phase or phases in another example where the substitution or addition is obviously workable.

35 The evaluation of the materials of cyclic structure content and/or aromatics referred to in the foregoing and in the annexed claims, is secured by recourse to the method disclosed under the caption "Neutral oils of coal hydrogenation—action of sulfuric acid," Industrial and Engineering Chemistry, Industrial edition, volume 32, page 1614 et seq., December 1940.

40 While the various examples disclose the use of definite catalyst with definite controls of the examples, it is to be understood that the catalysts are interchangeable with the definite controls of the examples, and any of the named catalysts, their equivalents or in combination are 45 usable in any of the examples. The examples given, and the catalysts linked therewith are for 50 purposes of illustration only.

55 Minor changes may be made within the scope of the appended claims without departing from the spirit of the invention. In the claims affixed to this specification no selection of any particular 60 modification is intended to the exclusion of other modifications thereof, and the right to subsequently make claims to any modification not covered by these claims is expressly reserved.

We claim:

65 1. The process of inducing toxicity into a relatively high boiling mixture of petroleum fractions characterized by a substantial percentage of materials of cyclic structure content, said cyclic structures having inhibited toxicity due to toxicity diluents which appear as integral parts thereof, which comprises: contacting said relatively high boiling mixture of petroleum fractions with a relatively low boiling oil of cyclic content adapted to receive as an integral part 70 thereof at least a portion of said toxicity dilu- 75

ents of said mixture; rendering the mixture of petroleum fractions more toxic by heat treating the contacted materials at a temperature selected between the limits of about 350-600° C. whilst under superatmospheric pressure for a period not in excess of about two hours, said period being so selected with reference to the chosen temperature and pressure as to jointly provide newly formed low boiling materials in said mixture of petroleum fractions, transference of at least a portion of said toxicity diluents from the mixture of petroleum fractions to said relatively low boiling oil of cyclic content, a specific gravity in fractional parts of the heat treated mixture of petroleum fractions falling between the following limits:

Fractions	Low limit	High limit
235-270° C.	0.850	1.0315
270-315° C.	0.914	1.0691
315-355° C.	0.973	1.1175

and recovering from the heat treated contacted materials at least a portion of the reacted and unreacted relatively low boiling materials of cyclic structure content whereby to provide the remainder thereof as material of induced toxic properties; and segregating from the beneficiated material an oil of the wood preservative type boiling preponderantly between 210° C. and 355° C., said oil characterized by induced toxic properties, and end point at least as high as about 355° C. and substantial residual material boiling above 315° C., the fractions 235-270° C., 270-315° C. and 315-355° C. of which have specific gravities falling between the limits above named.

2. The process of inducing toxicity into a relatively high boiling mixture of petroleum fractions characterized by a substantial percentage of materials of cyclic structure content, said cyclic structures having inhibited toxicity due to toxicity diluents which appear as integral parts thereof, which comprises: contacting said relatively high boiling mixture of petroleum fractions with a relatively low boiling oil of cyclic content adapted to receive as an integral part thereof at least a portion of said toxicity diluents of said mixture; rendering the mixture of petroleum fractions more toxic by heat treating the contacted materials at a temperature selected between the limits of about 350-600° C. whilst under superatmospheric pressure for a period not in excess of about two hours, said period being so selected with reference to the chosen temperature and pressure as to jointly provide newly formed low boiling materials in said mixture of petroleum fractions, transference of at least a portion of said toxicity diluents from the mixture of petroleum fractions to said relatively low boiling oil of cyclic content, a specific gravity in fractional parts of the heat treated mixture of petroleum fractions falling between the following limits:

Fractions	Low limit	High limit
270-315° C.	0.914	1.0691
315-355° C.	0.973	1.1175

and recovering from the heat treated contacted materials at least a portion of the reacted and unreacted relatively low boiling materials of cyclic structure content whereby to provide the remainder thereof as material of induced toxic

properties; and segregating from the beneficiated material an oil of the wood preservative type boiling preponderantly between 210° and 355° C., said oil characterized by induced toxic properties, and end point at least as high as about 355° C. and substantial residual material boiling above 315° C., the fractions 270-315° C. and 315-355° C. of which have specific gravities falling between the limits above named.

3. The process of inducing toxicity into a relatively high boiling mixture of petroleum fractions characterized by a substantial percentage of materials of cyclic structure content, said cyclic structures having inhibited toxicity due to toxicity diluents which appear as integral parts thereof, which comprises: contacting said relatively high boiling mixture of petroleum fractions with a relatively low boiling oil of cyclic content adapted to receive as an integral part thereof at least a portion of said toxicity diluents of said mixture; rendering the mixture of petroleum fractions more toxic by heat treating the contacted materials in the presence of a metallic chloride as catalytic agent, at a temperature selected between the limits of about 70-225° C. whilst under superatmospheric pressure for a period not in excess of about two hours, said period being so selected with reference to the chosen temperature and pressure as to jointly provide newly formed low boiling materials in said mixture of petroleum fractions, transference of at least a portion of said toxicity diluents from the mixture of petroleum fractions to said relatively low boiling oil of cyclic content, a specific gravity in fractional parts of the heat treated mixture of petroleum fractions falling between the following limits:

Fractions	Low limit	High limit
235-270° C.	0.850	1.0315
270-315° C.	0.914	1.0691
315-355° C.	0.973	1.1175

and recovering from the contacted heat treated materials at least a portion of the reacted and unreacted relatively low boiling materials of cyclic structure content whereby to provide the remainder thereof as material of induced toxic properties; and segregating from the beneficiated material an oil of the wood preservative type boiling preponderantly between 210° C. and 355° C., said oil characterized by induced toxic properties, and end point at least as high as about 355° C. and substantial residual material boiling above 315° C., the fractions 235-270° C., 270-315° C. and 315-355° C. of which have specific gravities falling between the limits above named.

4. The process of inducing toxicity into a relatively high boiling mixture of petroleum fractions characterized by a substantial percentage of materials of cyclic structure content, said cyclic structures having inhibited toxicity due to toxicity diluents which appear as integral parts thereof, which comprises: contacting said relatively high boiling mixture of petroleum fractions with a relatively low boiling oil of cyclic content adapted to receive as an integral part thereof at least a portion of said toxicity diluents of said mixture; rendering the mixture of petroleum fractions more toxic by heat treating the contacted materials in the presence of a metallic chloride as catalytic agent, at a temperature selected between the limits of about 70-250° C. whilst under superatmospheric pressure for

a period not in excess of about two hours, said period being so selected with reference to the chosen temperature and pressure as to jointly provide newly formed low boiling materials in said mixture of petroleum fractions, transference of at least a portion of said toxicity diluents from the mixture of petroleum fractions to said relatively low boiling oil of cyclic content, a specific gravity in fractional parts of the heat treated mixture of petroleum fractions falling between the following limits:

Fractions	Low limit	High limit
270-315° C.	0.914	1.0691
315-355° C.	0.973	1.1175

and recovering from the heat treated contacted materials at least a portion of the reacted and unreacted relatively low boiling materials of cyclic structure content whereby to provide the remainder thereof as material of induced toxic properties; and segregating from the beneficiated material an oil of the wood preservative type boiling preponderantly between 210° C. and 355° C., said oil characterized by induced toxic properties, and end point at least as high as about 355° C. and substantial residual material boiling above 315° C., the fractions 270-315° C. and 315-355° C. of which have specific gravities falling between the limits above named.

5. The process of inducing toxicity into a relatively high boiling mixture of petroleum fractions characterized by a substantial percentage of materials of cyclic structure content, said cyclic structures having inhibited toxicity due to toxicity diluents which appear as integral parts thereof, which comprises: contacting said relatively high boiling mixture of petroleum fractions with a relatively low boiling oil of cyclic content adapted to receive as an integral part thereof at least a portion of said toxicity diluents of said mixture; rendering the mixture of petroleum fractions more toxic by heat treating the contacted materials at a temperature selected between the limits of about 350-600° C. whilst under superatmospheric pressure for a period not in excess of about two hours, said period being so selected with reference to the chosen temperature and pressure as to jointly provide newly formed low boiling materials in said mixture of petroleum fractions, transference of at least a portion of said toxicity diluents from the mixture of petroleum fractions to said relatively low boiling oil of cyclic content, a specific gravity of materials of cyclic structure content in fractional parts of the heat treated mixture of petroleum fractions falling between the following limits:

Fractions	Low limit	High limit
235-270° C.	0.935	1.0756
270-315° C.	0.973	1.0933
315-355° C.	1.027	1.1285

and recovering from the heat treated contacted materials at least a portion of the reacted and unreacted relatively low boiling materials of cyclic structure content whereby to provide the remainder thereof as a material of induced toxic properties; and segregating from the beneficiated material an oil of the wood preservative type boiling preponderantly between 210° C. and 355° C., said oil characterized by induced toxic properties, and end point at least as high as about 355° C.

and substantial residual material boiling above 315° C., the fractions 235-270° C., 270-315° C. and 315-355° C. of which contain materials of cyclic structure content having specific gravities falling between the limits noted above.

6. The process of inducing toxicity into a relatively high boiling mixture of petroleum fractions characterized by a substantial percentage of materials of cyclic structure content, said cyclic structures having inhibited toxicity due to toxicity diluents which appear as integral parts thereof, which comprises: contacting said relatively high boiling mixture of petroleum fractions with a relatively low boiling oil of cyclic content adapted to receive as an integral part thereof at least a portion of said toxicity diluents of said mixture; rendering the mixture of petroleum fractions more toxic by heat treating the contacted materials at a temperature selected between the limits of about 350-600° C. whilst under superatmospheric pressure for a period not in excess of about two hours, said period being so selected with reference to the chosen temperature and pressure as to jointly provide newly formed low boiling materials in said mixture of petroleum fractions, transference of at least a portion of said toxicity diluents from the mixture of petroleum fractions to said relatively low boiling oil of cyclic content, a specific gravity of materials of cyclic structure content in fractional parts of the heat treated mixture of petroleum fractions falling between the following limits:

Fractions	Low limit	High limit
270-315° C.	0.973	1.0933
315-355° C.	1.027	1.1285

and recovering from the heat treated contacted materials at least a portion of the reacted and unreacted relatively low boiling materials of cyclic structure content whereby to provide the remainder thereof as a material of induced toxic properties; and segregating from the beneficiated material an oil of the wood preservative type boiling preponderantly between 210° C. and 355° C., said oil characterized by induced toxic properties, and end point at least as high as about 355° C. and substantial residual material boiling above 315° C., the fractions 270-315° C. and 315-355° C. of which contain materials of cyclic structure content having specific gravities falling between the limits noted above.

7. The process of inducing toxicity into a relatively high boiling mixture of petroleum fractions characterized by a substantial percentage of materials of cyclic structure content, said cyclic structures having inhibited toxicity due to toxicity diluents which appear as integral parts thereof, which comprises: contacting said relatively high boiling mixture of petroleum fractions with a relatively low boiling oil of cyclic content adapted to receive as an integral part thereof at least a portion of said toxicity diluents of said mixture; rendering the mixture of petroleum fractions more toxic by heat treating the contacted materials in the presence of a metallic chloride as catalytic material, at a temperature selected between the limits of about 70-250° C. whilst under superatmospheric pressure for a period not in excess of about two hours, said period being so selected with reference to the chosen temperature and pressure as to jointly provide newly formed low boiling materials in said mixture of petroleum fractions, transference

of at least a portion of said toxicity diluents from the mixture of petroleum fractions to said relatively low boiling oil of cyclic content, a specific gravity of materials of cyclic structure content in fractional parts of the heat treated mixture of petroleum fractions falling between the following limits:

Fractions	Low limit	High limit
235-270° C	0.935	1.0756
270-315° C	0.973	1.0933
315-355° C	1.027	1.1285

and recovering from the heat treated contacted materials at least a portion of the reacted and unreacted relatively low boiling materials of cyclic structure content whereby to provide the remainder thereof as a material of induced toxic properties; and segregating from the beneficiated material an oil of the wood preservative type boiling preponderantly between 210° C. and 355° C., said oil characterized by induced toxic properties, and end point at least as high as about 355° C. and substantial residual material boiling above 315° C., the fractions 235-270° C., 270-315° C. and 315-355° C. of which contain materials of cyclic structure content having specific gravities falling between the limits noted above.

8. The process of inducing toxicity into a relatively high boiling mixture of petroleum fractions characterized by a substantial percentage of materials of cyclic structure content, said cyclic structures having inhibited toxicity due to toxicity diluents which appear as integral parts thereof, which comprises: contacting said relatively high boiling mixture of petroleum fractions with a relatively low boiling oil of cyclic content adapted to receive as an integral part thereof at least a portion of said toxicity diluents of said mixture; rendering the mixture of pe-

trolem fractions more toxic by heat treating the contacted materials in the presence of a metallic chloride as catalytic material, at a temperature selected between the limits of about 70-275° C. 5 whilst under superatmospheric pressure for a period not in excess of about two hours, said period being so selected with reference to the chosen temperature and pressure as to jointly provide newly formed low boiling materials in said mixture of petroleum fractions, transference of at least a portion of said toxicity diluents from the mixture of petroleum fractions to said relatively low boiling oil of cyclic content, a specific gravity of materials of cyclic structure content in fractional parts of the heat treated mixture of petroleum fractions falling between the following limits:

Fractions	Low limit	High limit
270-315° C	0.973	1.0933
315-355° C	1.027	1.1285

and recovering from the heat treated contacted materials at least a portion of the reacted and unreacted relatively low boiling materials of cyclic structure content whereby to provide the remainder thereof as a material of induced toxic properties; and segregating from the beneficiated material an oil of the wood preservative type boiling preponderantly between 210° C. and 355° C., said oil characterized by induced toxic properties, and end point at least as high as about 355° C. and substantial residual material boiling above 315° C., the fractions 270-315° C. and 315-355° C. of which contain materials of cyclic structure content having specific gravities falling between the limits noted above.
